UNITED STATES PATENT OFFICE.

ANTHONY MARCELLI, OF NEW YORK, N. Y.

TROUSERS-PROTECTOR.

1,211,472.

Specification of Letters Patent.

Patented Jan. 9, 1917.

Application filed February 25, 1916. Serial No. 80,375.

To all whom it may concern:

Be it known that I, ANTHONY MARCELLI, a subject of the King of Italy, residing at New York, in the county and State of New

5 York, have invented certain new and useful Improvements in Trouser-Protectors, of which the following is a full, clear, and exact specification.

This invention relates to trousers protectors, and has for its object to provide means for preventing the bottoms of trousers from becoming splashed and soiled by water and mud in wet weather. As the rear portions 10 of the bottoms of the legs of the trousers are the parts most apt to become splashed, special provision is made in the formation 15 of the invention to protect such parts.

Another object is to produce protectors of this kind which may be easily attached 20 to the bottoms of the trousers and quickly detached when their use is no longer required.

The invention will be first hereinafter described in connection with the accompanying 25 drawings, which constitute part of this specification, and then more specifically defined in the claim at the end of the description.

In the accompanying drawings, wherein 30 similar reference characters are used to designate corresponding parts throughout the several views:—Figure 1 is a side view of the bottom of one leg of a pair of trousers, showing a protector made substantially in accordance with this invention attached thereto. Fig. 2 is a section on the line 35 II—II of Fig. 1, and Fig. 3 is a detailed inner face view of the protector as it appears when spread out flat.

40 Referring more particularly to the drawings, 1 designates the bottom portion of one leg of a pair of trousers having the usual cuff 2. If the trousers are not finished with

cuffs at the bottom, they may be temporarily formed by turning up the bottom of 45 each leg for the purpose of attaching the protectors.

The protector is formed with an upwardly extending rear portion 3 and forwardly extending portions 4 adapted to meet at the front crease of the trousers. Said protector may be made of mercerized or rubber coated material thick enough or stiff enough to make the upwardly extending portion 3 stand up in the position shown when in use. 50 Along the bottom of the protector there is an inwardly and upwardly turned fold 5 of the material adapted to be arranged inside the bottom edge of the cuff 2.

The protector is supported in proper position by a number of hooks 6 secured to the inner face of the protector and adapted to be engaged with the upper edge of the cuff as shown in Figs. 1 and 2. It will be noted that the inwardly turned fold 5 prevents the 60 protector from working up out of proper position.

The front ends of the portions 4 are secured together by a hook 7 attached to one of said portions and an eye 8 attached to 70 the other of said portions 4. It will be understood of course that other suitable fastening means may be employed instead of the hooks and eye.

Having thus described my invention, what 75 I claim as new and desire to secure by Letters Patent is:

The combination with trousers having cuffs on their bottoms, of a protector to envelop said cuffed bottoms, and hooks on the 80 inner face of the protector for engaging the upper edge of the cuff to support said protector in proper position.

In testimony whereof I have signed my name to this specification.

ANTHONY MARCELLI.
